MICROPHONE RELAY HEARING APPARATUS

Armand Veilleux, St. Georges Beauce, Quebec,
Canada

Application April 19, 1933, Serial No. 666,887

1 Claim. (Cl. 179—107)

The invention relates to a microphone relay hearing apparatus, as described in the present specification and illustrated in the accompanying drawing that forms part of the same.

5 The invention consists essentially in establishing a magnetic field from which a vibrating armature projects as a dental contact, cooperating with an amplifier and a source of electric current, as pointed out in the claim for novelty 10 following a description in detail of the contact member with general reference to the connections.

The objects of the invention are to enable the deaf to hear with distinctness not usually attainable with what are known as earphones, and thereby eliminate many of the difficulties incident to social and business intercourse by those suffering from this great affliction; to furnish a portable equipment for each person requiring the apparatus, whereby it can be brought into instant use and insure perfect service in this direction for any and all persons suffering from a weakness in so far as their hearing is concerned, and generally to provide a convenience to deaf people by 20 a new system of telephone communication, not heretofore available to the deaf.

In the drawing, Figure 1 is a side elevational view of the apparatus.

Figure 2 is a longitudinal sectional view.

30 Figure 3 is an end elevational view.

Figure 4 is a cross sectional view on the line 4—4 in Figure 1.

Figure 5 is a cross sectional view on the line 5—5 in Figure 1.

35 Figure 6 is a perspective detail of the vibrator.

Figure 7 is an assembled view of the parts to this instrument.

Like numerals of reference indicate corresponding parts in the various figures.

40 Referring to the drawing, the numeral 15 indicates the vibrating device in which the armature 16 is set in a magnetic field 17, the whole being enclosed in a casing 18 preferably of copper, and made in the form of a handle 19 swelling into a 45 case 20 containing the electrical binding posts 21 and 22 to which the wires from the cable 23 are respectively connected, these binding posts being connected by the wires 24 and 25 to the electromagnet proper, which has the coil 26 enclosed between the body pieces 27 and 28, which in turn are held between the bars 29 and 30 of what is commonly termed a horse-shoe magnet.

50 The iron body pieces 27 and 28 of the magnet are held apart by the brass ring spacers 31 and 55 32, encircling the vibrating armature 33. This

armature is held between the screws 34 and 35, one from each side, having the insulating heads 36 and 37 and this vibration is limited by the head 38 of the armature operating within the slots 39 in the body pieces 27 and 28.

60 The dental contact 40 projects from the head 38 and preferably terminates in a ball end, the projecting portion of the contact extending through the orifice 42 at the end of the case 20, thus at one end of the vibrating device, the contact extends outwardly while at the other end, the grip forms the means of handling the vibrator.

65 It will thus be seen that there is a magnet field established within the case, and that this can be operated in contact with the teeth of the 70 deaf person, so that this person plainly hears any sound amplified sufficiently to be recognized.

75 The cable 23 extends to the amplifier 45, which is of conventional construction and contains a battery for electrifying the magnetic field and for use in the amplifier, and connected to this amplifier by the wire 43 is a microphone 44 through which the person speaks to the deaf person, and this sound is amplified and by means of the magnetic vibrating contact, the sound reaches the 80 ears of the deaf person.

What I claim is:—

A microphone relay hearing apparatus comprising a microphone a sound amplifier and a magnetic vibrator comprising a horse shoe magnet embracing the field of an electro-magnet on either side of a central dental vibrating armature held by screws having insulated heads and having a head forming a stop limit in a slot between the body parts, said dental armature terminating in a contact to be held to the teeth and said electro-magnet being electrically connected to said amplifier and microphone.

ARMAND VEILLEUX.
